(57) CLAIM

The ornamental design for an exercise equipment for pets, as shown and described.

DESCRIPTION

FIG. 1 is a perspective view of exercise equipment for pets; FIG. 2 is a front view thereof, the rear view being a mirror image;

FIG. 3 is a left side view thereof;

FIG. 4 is a right side view thereof;

FIG. 5 is a top view thereof;

FIG. 6 is a bottom view thereof;

FIG. 7 is a front view showing a movable portion being in an alternate position; and,

FIG. 8 is a left side view of FIG. 7.

The broken lines are for illustrative purposes only and form no part of the claimed design.
